UNITED STATES PATENT OFFICE.

JOSEPHUS GUTHRIE, OF DECLO, IDAHO.

WIRE-FENCE STRETCHER.

Application filed March 2, 1927. Serial No. 172,057.

The present invention relates to improvements in wire stretchers and has reference more particularly to a device for stretching woven wire fences and for holding the same taut in order to permit the fence to be properly stapled to the fence posts.

One of the important objects of the present invention is to provide a woven wire fence structure of the above mentioned character which will, at all times, be positive and efficient as to its operation, means being provided whereby the fence wire engaging hooks may be adjustably connected to the shaft forming the windlass, so that woven wire fences of various widths may be accommodated.

A still further object is to provide a woven wire fence stretcher of the above mentioned character, which is simple in construction, strong and durable and further well adapted for the purpose for which it is designed.

Other objects and advantages of the invention will become apparent from the course of the following detailed description.

In the accompanying drawings forming a part of this application and in which like reference characters designate like parts throughout the views:

Figure 1 is a side elevation of the fence stretcher embodying my invention, showing the parts in position for stretching the woven wire fence.

Figure 2 is a similar view, taken at right angles to Figure 1.

Figure 3 is a top plan view.

Figure 4 is a sectional view, taken approximately on the line 4—4 of Figure 1, looking in the direction of the arrows, and

Figure 5 is an enlarged fragmentary detail section of the tubular shaft, showing the manner in which the ratchet wheel is adjustably mounted thereon.

In the drawings, wherein for the purpose of illustration is shown the preferred embodiment of my invention, the numeral 1 designates an elongated flat bar or standard, which is adapted to be disposed adjacent one side face of the corner post A, and for the purpose of securing the bar or standard in a rigid position against the post, I provide the post engaging hooks 2 at the upper and lower end portions of the bar, the same being hingedly connected to the rear edge of the standard as at 3. The manner in which the pivoted hooks 2 engage the corner post A, is

more clearly illustrated in Figure 3 of the drawings.

Extending longitudinally along the opposite edge of the standard or bar 1 and supported in suitable bearings or brackets 4 is the elongated roller 5. A purpose of this roller will be hereinafter more fully described.

Extending laterally from the outer side face of the bar or standard 1 are the upper and lower horizontal arms 6 and 7 respectively. A tubular shaft 8 extends vertically through the outer ends of these arms 6 and 7 and is adapted for rotation in the openings provided therefor in the arms. The tubular shaft 8 is of relatively great length and is adapted to provide a windlass, for the purpose to be presently described. The shaft 8 is rotated through the medium of a suitable handle 9, which extends through a collar 10 and through registering openings in the upper end of the shaft on which the collar is mounted. The handle is of such construction as to permit the same to be connected to either end of the shaft, it of course being understood that each end of the shaft is of identical construction.

The tubular shaft 8 is provided with a series of vertically spaced registering openings, such as are shown at 11, adjacent each end thereof and the purpose of these openings will also be apparently obvious later on, in the further description of the fence wire stretching means. A pair of ratchet wheels 12 are adapted for slidable movement along the intermediate portion of the tubular shaft 8, and each ratchet wheel is formed with the hub portion 13, through which extends radially the set screw 14 and the inner end of this set screw is adapted to engage the tubular shaft 8 for adjustably securing each of the ratchet wheels on the shaft.

The ratchet wheels are preferably located on the shaft adjacent the bottom and upper face of the upper and lower laterally extending arms respectively, as is clearly illustrated in Figure 1. Cooperating with each ratchet wheel is a pivoted pawl 15 secured to the inner face of each arm, the inner end of each pawl being held normally in engagement with the teeth 16 of the respective ratchet wheel through the medium of the spring 17. The outer end of each pawl is bent to provide a handle 18, whereby the inner end of the pawl may be moved out of engagement with the

ratchet teeth 16, whereby to permit the rotation of the shaft 8, in a reverse direction.

For the purpose of bracing the stretching means, I provide a pair of chains, such as are shown at 19, the same being secured at one end to the outer end of each arm, as at 19', the other end of each of said chains being engaged around a post B, which is disposed at right angles to the corner post A. The arrangement of the bracing means is clearly shown in Figures 2 and 3.

The fence wire stretching means comprises upper and lower cables 20 and 21 respectively. A collar 22 is connected to one end of each of said cables and the same is disposed over the rotatable shaft 8. Each cable is trained over a pulley 23 supported in a hook carrying member 24, a hook 25 being swivelly associated with the member. The other end 20 of each cable has a hook 26 connected thereto, and these hooks are adapted for engagement in any one of the upper and lower series of openings 11 formed in the shaft 8. This construction provides a means whereby the cables may be properly placed with respect to each other, in order to accommodate woven wire fences of different widths and further in order to permit of a direct pull upon the end of the wire fence which is to be stretched.

30 The hooks 25 are adapted to engage the upper and lower strands C of the woven wire fence, in the manner as clearly shown in Figure 1, and with the parts thus arranged, it is obvious that when the handle 9 is turned in one direction, the shaft 8 will be rotated, thus causing the hooked end of each cable to be wound around the shaft, and thereby exert a forward pull on the woven wire fence to effect the stretching thereof across the corner 35 post A and when the woven wire fence has been stretched to the proper degree, the same will be maintained in such stretched position by the pawl and ratchet mechanism hereto-

45 fore described, and the fence wire may be then stapled to the post A.

It will thus be seen from the foregoing description that I have provided a simple and efficient wire stretcher which can be readily and easily set up in position for use, and such a device will save considerable time and 50 labor in stretching woven wire fences.

55 While I have shown the preferred embodiment of my invention, it is to be understood that various changes in the shape, size and arrangement of parts may be made, without departing from the spirit of the invention or the scope of the appended claim.

What I claim is:

60 In a wire fence stretcher, the combination of a vertical bar, post engaging hooks hinged- 65 ly secured to the upper and lower end portions of the bar for securing the same against the post, a pair of arms extending laterally from the respective ends of the bar and being rigidly secured thereto, a vertical shaft 70 journaled for rotation in the outer ends of the arms, upper and lower fence wire engaging hooks, carriers therefor, a pulley arranged in each carrier, a cable trained over each pulley, a collar attached to one end of each cable and being slidable on said shaft, said shaft being provided with a series of spaced 75 openings whereby hooks carried by the other ends of the cables may be adjustably connected to the shaft, the hooked ends of the cables being adapted to be wound around the shaft when the same is rotated to effect the stretching 80 of the wire fence, ratchet wheels secured on the shaft adjacent the outer ends of the respective arms, pivoted pawls carried by said arms for cooperation with ratchet wheels to prevent reverse rotation of the shaft, and bracing means for the outer ends of said laterally extending arms.

85 In testimony whereof I affix my signature.
JOSEPHUS GUTHRIE.
